UNITED STATES PATENT OFFICE.

ABRAHAM ANDERSON, OF GALESBURG, ILLINOIS, ASSIGNOR TO G. D. COLTON & CO., OF SAME PLACE.

CORN-PLANTER CHECK-ROWER.

SPECIFICATION forming part of Letters Patent No. 293,395, dated February 12, 1884.

Application filed October 20, 1883. (No model.)

To all whom it may concern:

Be it known that I, ABRAHAM ANDERSON, a citizen of the United States, residing at Galesburg, in the county of Knox and State 5 of Illinois, have invented certain new and useful Improvements in Corn-Planter Check-Rowers; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to that class of check-row attachments to corn-planters in which a rock-shaft located transversely on the planter is provided with a forked lever or levers at each of its ends, which levers are swung by 20 impact with knots or tappets on a stretched wire, and thereby give motion to the rock-shaft; and my invention is designed to improve the means for transmitting motion from the rock-shaft to the slide-bar generally used 25 to actuate the seed measuring and discharging devices; and it consists in constructions and combinations hereinafter described and claimed.

30 The accompanying drawings show a mode of carrying my invention into practice, in which—

Figure 1 is a top plan; Fig. 2, a sectional elevation in line *x x* in Fig. 7. Fig. 3 is same sectional elevation as Fig. 2, but shows the parts in different relative positions from said figure; Fig. 4, a detail—a plan of the adjacent ends of the divided rock-shaft and adjacent parts in section; Fig. 5, a perspective of the central parts shown at Fig. 1; Fig. 6, a perspective of one of the adjacent ends of the rock-shaft; Fig. 7, a top plan of the parts shown at Fig. 5, but in different relative positions from that shown at Fig. 5.

Referring to the drawings by letters, the 45 same letter indicating the same part in the different figures, A represents the base-bar; B B, the heads, with guide-pulleys C c c; D, the rock-shaft, with a forked lever, d, on each end; E, the tension-spring, connected at one 50 end with the rock-shaft, as hereinafter de-

scribed, and at its other end with a fixed part of the planter, or a projection from the bar A; F, the tappet-wire, with tappets f secured thereto.

The foregoing parts, described by letters of 55 reference, constitute parts of an ordinary check-rower, and need not be any more fully herein described, as the constructions, with variations, mode of operation, and manner of seating and fixing upon a corn-planter, are well 60 known.

About the mid-length portion of the bar A is fixed thereto a bed-plate or base, G, which carries bearings for the parts hereinafter described.

H is an oscillating bar journaled at its mid-length on a stud-bolt, g, which is fixed to a projecting part of the base G.

I I' are sliding arms journaled at their rear ends, one to each end of the bar H. Each 70 arm I I' has a slot, i, in its forward end. The arms I I' are connected at or near the mid-length portion of each by a link, J, which is journaled or hinged to each arm I I'. The lower surfaces of the arms I I' are in same 75 plane as and slide upon the elevated flat portion G' of the plate G, and the part G' preferably has a cover or dust-excluder, g', which is shown broken away at Figs. 1, 5, and 7, to show working parts beneath. An arm, h, 80 projects from the bar H, to which arm h a rod, h', is hinged, which extends to and may be connected in any ordinary manner with the slide-bar which actuates the seed-slides, so that oscillating the bar H will operate the 85 seed-slides. The rock-shaft D is a divided shaft, or made in two parts, D' D'', and the adjacent ends of these parts are each provided with a projecting tappet-arm, d' d'', respectively. K is a rocking plate loosely 90 seated on the shaft D, so as to receive the adjacent ends of each part D' D'', as the most plainly shown at Fig. 4, and in such manner that the arms d' d'' are within a triangular-shaped recess, k, in the plate K. The lower 95 end of the rocking plate K terminates in a hook, k', to which one end of the spring E is attached, its other end being attached to a hook, e, pendent from the base G. A pawl, L, is journaled at its mid-length to the upper 100

end of the rocking plate K. The outer end, l, of the pawl L is weighted to overbalance its other end, l', which reciprocates, as herein-after described, in a slot, g'', in the plate G. 5 The end l' is preferably formed about as shown—that is, with a part, l'', which comes in contact with the arms I I', and a projecting part, l''', which passes beneath the arms I I'. In their normal positions the arms d' d'' lie in 10 or about the same horizontal plane, as shown by arm d'' at Fig. 5.

As shown in the drawings, the tappet-wire is in contact with the forked lever which is fixed to the part D'' of the divided rock-shaft, 15 and at Fig. 1 a knot or tappet, f, is shown in position to act upon and swing the forked lever rearward in the ordinary manner as the planter advances in the direction of the arrow seen at same figure. This movement of the 20 forked lever will partially rotate the shaft D'', and the arm d'', already in contact with the upper wall of the recess k, will swing the upper end of the plate K rearward of the planter, and thereby thrust the pawl L rearward, and, 25 assuming the parts in relative positions shown at Figs. 1 and 2, the end l'' of the pawl will come in contact with the forked end of the arm I and push said arm rearward to its position shown at Figs. 3 and 7, and thereby swing the arm 30 H and give a throw to the seed-slides, as already described. The tappet then, escaping from the forked lever, will free the parts, and the spring E will then return the rocking-plate K and pawl L to their positions shown 35 at Figs. 2 and 7, and the plate K, in so returning, will act on the arm d'', and return it and shaft D'' to their positions shown at same figure, and also at Figs. 1 and 5. The movement of the arm I rearward, as last described, 40 in swinging the bar H, thrusts the arm I' forward into the position shown at Figs. 3 and 5, and ready for the action of the pawl L at its next throw given by impact of the forked lever and the next recurring tappet on the 45 wire F. As the arm I moves rearward of the planter, as last described, the pawl L being made to move in a straight path by the slot g'', its end l'', resting in the fork i of said arm, will cause the end of the arm I which is in 50 contact with the pawl to move in a straight line or path also, and the link J will cause the slotted end of the arm I' to swing outwardly to pass the slotted end of the arm I, as shown by dotted lines at Fig. 7; and, further, as the 55 arm I reaches the rear end of its movement, (seen at Fig. 5,) the link J will bring the forked end of the arm I' into proper position, as shown at same figure, for the action of the pawl L at its next movement. The weighted end of 60 the pawl L will keep its end l' up in position for the contact with the arms I I' hereinbefore described, and as the pawl is drawn backward by the plate K this weighted end will permit the other end to lower to pass beneath whichever arm, I or I', it may have to pass beneath 65 in so returning.

It will be seen more plainly at Fig. 3 that

when the arm d'' is made to move the plate K, pawl L, and one of the arms I or I', the recess k is of such size that it will not move 70 the arm d', and hence it and the shaft D' will remain at rest while the shaft D'' is operating the seeding devices, and thereby not be subjected to useless wear. When the shaft D' is 75 operating the seeding devices, the shaft D'' will then remain at rest. Whichever arm d' or d'' has acted to rock the plate K backward at its upper end will be acted on by the plate in its return movement, caused by the spring E, to return the arm d' or d'' to its 80 normal position, as will be evident from the position of arm d'' at Fig. 3.

The pawl L, as will be evident, may be otherwise formed than what I have shown, and may be held in a straight path without 85 the slot g'', and the forked ends to the arms I I' may be dispensed with. It will also be evident that the shaft D may be made in one undivided shaft, to which the plate K may be fixed, and operate the device as is done with 90 the divided shaft, except in that both ends of the shaft will operate at the same time; hence I do not limit my claims to the special construction of any of the parts; but

What I claim as new, and desire to secure 95 by Letters Patent, is—

1. In a check-rower, in combination with the oscillating bar H, connected by suitable mechanism with the planter seed-slides, and the arms I I', hinged or journaled one to each 100 end of the bar H, the link J, hinged to said arms, and adapted to swing one of them in a curved path in its return movement to pass the other, which moves in a straight or nearly straight path in its direct movement, substantially as and for the purpose specified. 105

2. In a check-rower, in combination with the oscillating bar H and the arms I I', hinged or journaled one to each end of said bar, and connected by a link, J, a pawl adapted to move 110 in a straight line in contact with the arms I I' alternately, substantially as and for the purpose specified.

3. In a check-rower, in combination with the oscillating bar H, arms I I', hinged or journaled to said bar and connected by a link, J, the pawl L, and plate G', having a slot, g'', in which the pawl reciprocates and upon which the arms I I' slide, substantially as and for the purpose specified. 115

4. In a check-rower, in combination with the oscillating bar H, arms I I', hinged or journaled to said bar, connected by a link, J, and having each a fork, i, in its end, the pawl L, adapted to move in a straight path and to engage with a fork, i, in the arms I I' alternately, substantially as and for the purpose specified. 120

5. In a check-rower, in combination with the oscillating bar H, arms I I', hinged or journaled thereto, connected by a link, J, and provided with forks i at their ends, the pawl L, adapted to move in a straight path, with its part l''' in the slot g'' in the plate G', and its 125

part l'' in position to act on the arms $I I'$ alternately, substantially as and for the purpose specified.

6. In a check-rower, in combination with the oscillating bar H , arms $I I'$, hinged or journaled thereto and connected by a link, J , the weighted pawl L , hinged to the rocking plate K , which is oscillated by connection with the fork-carrying shaft D , substantially as and for the purpose specified.

7. In a check-rower, in combination with the oscillating bar H , arms $I I'$, hinged or journaled thereto and connected by a link, J , the weighted pawl L , hinged to the plate K , which is loosely seated on the divided shaft D , and has a recess, k , adapted to receive the arms $d' d''$, one on each end of the divided shaft, and to be actuated by one of said arms, while the other remains stationary, substantially as and for the purpose specified.

8. In combination, the oscillating bar H , with arms $I I'$ hinged thereto, and connected by a link, J , pawl L , and rocking plate K , loosely mounted on the ends of the shafts D'

D'' , and provided with a recess, k , which receives the arms $d' d''$ of said shafts, and the spring E , connected directly to the plate K , substantially as and for the purpose specified.

9. In combination, the two-part shaft $D' D''$, having arms $d' d''$, respectively, plate K , loosely seated on said shafts, and provided with a recess, k , pawl L , arms $I I'$, connected by link J , and oscillating bar H , substantially as and for the purpose specified.

10. In combination, the two-part shaft $D' D''$, having arms $d' d''$, respectively, plate K , loosely seated on the adjacent ends of said shafts, and provided with a recess, k , spring E , connected with the plate K , pawl L , arms $I I'$, links J , and oscillating bar H , substantially as and for the purpose specified.

In testimony whereof I affix my signature in presence of two witnesses.

ABRAHAM ANDERSON.
